United States Patent Office.

WILLIAM KOPLIN, OF NEW CASTLE, PENNSYLVANIA.

Letters Patent No. 77,199, dated April 28, 1868.

IMPROVEMENT IN SPIKE-MACHINES.

The Schedule referred to in these Letters Patent and making part of the same.

TO ALL WHOM IT MAY CONCERN:

Be it known that I, WILLIAM KOPLIN, of New Castle, Lawrence county, and State of Pennsylvania, have invented certain new and useful Improvements in Spike-Cutting Machines; and I do hereby declare the following to be a full, clear, and exact description of the same, reference being had to the accompanying drawings, which form part of this specification.

This is an improvement upon the spike-cutting machine for which Letters Patent, No. 61,214, were granted to me on the 15th day of January, 1867.

In the drawings—

Figure 1 is a plan of so much of the machine as is necessary to illustrate my present improvements.

Figure 2 represents a vertical section of the same at x x , fig. 1.

Similar letters of reference indicate corresponding parts.

The side dies or jaws g j , cutting-pointer K , lever m , cam o , and heading-tool b , may be substantially as described in my previous patent above referred to.

My present improvements relate chiefly to the way of applying and operating the sliding knife h .

The said knife is mounted in a stock, s , pivoted to a sliding carriage, t , and furnished with a spring, s' , which serves to press the knife h constantly down upon the stationary lower die K' .

u is an arm, projecting downward from the shaft m' of the lever m , to impart a backward and forward motion to the slide t and knife h .

v is a spring, bearing against the arm u with sufficient force to press the lever m upward in contact with the cam o .

The operation is as follows:

The heated bar (shown in red in fig.-2) may be fed in upon the knife h as a guide, the header b constituting a gauge as to length.

The lever m , being then pressed down by the rotation of the cam o , severs a blank by the die K acting against the end of the knife h .

This stage of the operation is represented in fig. 2. As the die K continues to descend, the knife h recedes in a horizontal direction, until the points of the two dies meet at an acute angle, by which time the blank is tightly squeezed between their whole length, and thus receives the required form for a spike, with the exception of the head, which latter is next formed by the heading-die b , which is forced up by any suitable means, not necessary to describe. The dies b and K then recede, and the completed spike is removed.

A great advantage of my improved machine, above described, is, that by it the blank is severed from the bar while gripped between the dies.

The sliding knife fits against the point of the cutting-die as the blank is severed, and then moves out of the way to permit the dies to complete the point which has been partially made in the act of cutting.

By this process the points are all made with perfect uniformity, are effectually prevented from spreading, and are less liable to fire.

Having thus described my invention, what I claim as new, and desire to secure by Letters Patent, is—

1. The cutter k , moving in the arc of a circle, in combination with the receding cutter h , substantially as and for the purpose set forth.

2. The combination and arrangement of the dies K K' , sliding cutter h , pivoted stock s , carriage t , arm u , springs s' v , lever m , and shaft m' , substantially as and for the purposes described.

WILLIAM KOPLIN.
